ABSTRACT

A multiple filter for cigarettes is manufactured by initially forming a rod which is divisible into mouthpieces having at least three sections with the central section containing particulate material. An inner wrapper for the sections is either preperforated or punctured at the central section to facilitate the introduction of the granular material. Thereafter, either an outer wrap or a tape of reduced width is applied over the inner wrap to close off and seal completely the central section. In order to provide more uniform fill of the particulate material, an intermittent rod manufacturing process is employed.

MULTIPLE FILTER HAVING A LOOSE GRANULE SECTION WITH PERFORATED INNER WRAPPER

REFERENCE TO RELATED PATENTS

This application relates to the general subject matter disclosed in commonly assigned U.S. Pat. Nos. 3,482,488, granted Dec. 9, 1969, and 3,524,454, granted Aug. 18, 1970.

BACKGROUND OF THE INVENTION

In the above referenced patents, a multiple filter rod construction is disclosed in which components of the same or different character are interdigitated between a second group of spaced components on a traveling inner wrapper. This wrapper is of a width slightly less than the circumference of the components and is formed around a major portion of the circumferentially extending periphery of these components. Accordingly, a top opening is defined between the marginal side edges of the inner wrapper; and this opening is in communication with the space of selected size between components. The partially wrapped components pass through a particulate material dispensing station at which the spaces between components are filled with this material through the top opening. In order to increase the rate of fill as well as to assure optimum density of the particulate material, suction may be applied through the first wrapper below the discharge opening of the dispenser. The partially wrapped components and interposed particulate sections pass through a second wrapping station at which a second wrapper of increased width is folded around the rod to cover the top opening defined by the inner wrapper. The marginal side edges of the outer wrapper are overlapped and suitably sealed together. The continuous rod is then subdivided into the desired length of rods which are then introduced into conventional filter tip attaching machinery forming cigarettes with the mouthpiece having two spaced components of certain character and interposed particulate section.

While multiple filters manufactured in accordance with the teachings of the foregoing patents have proved to be eminently satisfactory and successful, it has been found that on occasion the particulate material introduced into the space between the components would, from time to time, enter the relatively shallow cavity between the marginal side edges of the inner wrapper and the components and eventually be disposed therein even after the application of the outer wrapper. Of course, this not only detracted from the quality of the filter, but on certain occasions did affect the filtering efficiency.

SUMMARY OF THE INVENTION

The present invention proposes to eliminate the aforesaid problems by assuring the maintenance of the particulate material within the central section between components.

A further object is to improve the operating efficiency of a multiple filter having a particulate section and at the same time assuring optimum quality control of the finished product.

Another object is to provide an intermittent manufacturing operation for a multiple filter having a particulate section which provides for more precise fill of the central section while providing a cleaner operation.

Other objects and advantages will become apparent from the following detailed description which is to be taken in conjunction with the accompanying drawings.

BRIEF DESCRIPTION OF THE DRAWINGS

FIG. 1 is a fragmentary top view of the dual wrapping operation whereby spaced filter components are secured within the inner wrapper to provide space of predetermined size between the components to which access is possible by means of the perforated openings through which the selected particulate material may be introduced and which are sealed by the outer wrapper;

FIG. 2 is a fragmentary perspective view of a similar operation showing the openings sealed off by a narrow tape;

FIG. 3 is a fragmentary plan view of an inner wrapper with only one of the side edges perforated or notched at predetermined intervals through which the particulate material may be introduced forming the central particulate section;

FIG. 4 is a similar plan view of the inner wrapper with holes spaced intermediate the marginal side edges, which holes may be either preformed or punched or perforated on the rod forming machine;

FIG. 5 is a view similar to FIG. 1 showing the inner wrap being punctured while on the rod forming machine and prior to the introduction of the particulate filtering material; and

FIG. 6 is a fragmentary elevational view showing the formation of a multiple filter rod of this invention in which the rod formation is intermittent to facilitate the introduction of the particulate material in the central section.

DETAILED DESCRIPTION

In FIG. 1, a dual wrap multiple filter rod is formed by initially providing a first inner wrapper 10 of a width at least equal to the circumference of the selected components 12a and 12b which may be of the same or different material. In the event the width of the inner wrapper 10 is greater than the circumference of the components 12a and 12b, the marginal side edges thereof will be overlapped and suitably secured to one another. The material selected for the wrap 10 may be of a thermoplastic nature or selected from a wide variety of other materials, including plastics, paper or the like, which will provide an essentially self-supporting rod prior to introducing the particulate material into the spaces between the components 12a and 12b. This will assure the uniform cross-section of the rod prior and subsequent to the filling operation. Where desired or necessary the spaced components 12a and 12b may be fused or otherwise suitably secured or bonded to the inner wrapper 10 to maintain the desired space relationship. In accordance with the embodiment of FIG. 1, the marginal side edges of the inner wrapper 10 are notched or otherwise suitably perforated at spaced intervals to provide openings through which the selected particulate material may be introduced into the central section 14. Thus, in this embodiment opposed notches or perforations 16a and 16b are performed and cooperate in defining the opening 18 which may be of any suitable length which is equal to or less than the space between the components 12a and 12b.

65

The partially wrapped rod with secured components 12a and 12b passes through a loose particulate material filling station which serves to introduce the selected particulate material 20 in the space 14.

The partially wrapped rod is then covered by an outer wrapper 22, the marginal side edges of which are in overlapped relationship whereby the wrapper completely embraces the exterior surfaces of the first wrapper 10 while closing or sealing the openings 18. The overlapped marginal side edges of the second wrapper 22 may be secured through the use of a seam paste of a type well known in the art and in the event a thermoplastic outer wrapper is utilized, its overlapped edges may be suitably fused or otherwise bonded together.

The completely wrapped rod is then passed through a conventional cut-off device which operates to cut the dual wrapped filter rod into predetermined lengths. These lengths are subsequently placed in conventional filter tip attachment machinery adapted to secure composite mouthpieces on cigarettes. These composite mouthpieces will include component 12a of material A, the particulate section of material 20 and component 12b of material B where material B may be the same as or different from material A and may be of the same or of unequal length. The particulate section may be of varying lengths depending upon material selected. The particulate material may be granular, powdered, flaked, flocculent or the like or any combination thereof and may include, but not necessarily limited to charcoal, alumina, silica gel, appropriate resins that may be modified or supplied with selected additives or other suitable filtering or conditioning materials.

In FIG. 2, an embodiment of the invention is disclosed in which the holes 18 of the inner wrapper 10 are closed or sealed by a tape 22a of relatively reduced width. Of course, a tape 22a is secured to the surfaces of the inner wrapper 10 in any suitable fashion.

In FIG. 3, an inner wrapper 10a is shown with notches 16c appearing along only one of the marginal side edges. As will be appreciated, the size and configuration of the notches may be varied within limits to facilitate and expedite the introduction of the selected particulate material.

The embodiment of inner wrapper 10b of FIG. 4 utilizes perforations 16d at the prescribed intervals intermediate the marginal side edges. These perforations 16d may be either preformed or punctured at the rod forming machine at any point prior to the introduction of the particulate material.

Towards this end, reference is made to FIG. 5 in which a perforator 24 operates in synchronization with the movement of the inner wrapper 10b. As shown, the perforator 24 is in the form of a rotatively driven wheel having peripheral laterally extending projections which puncture the inner wrapper 10b at the desired location between the spaced segments 12a and 12b prior to the particulate material loading station.

Referring now to FIG. 6, it will become evident that the present invention contemplates an intermittent rod forming operation as compared to the continuous operation disclosed in the above referenced patents. In this connection, the inner wrapper 10 formed about the spaced components 12a and 12b is stopped and indexed at predetermined intervals to register metering jets 26 with openings 18. Thereafter, the particulate material is introduced in the space 14. In this manner, optimum fill is obtained particularly when handling rel-

atively low density particulate material. In order to further improve the fill of certain particulate material, suction may be applied as indicated as was the case in connection with the disclosure of the above referenced 5 patents. Of course, both the application of suction and the dispensing from the metering jets 26 may be timed and synchronized with the indexing of the partially formed rod. When the interposed spaces 14 have been filled with the selected particulate material, the metering jets 26 will be deactivated and the suction, if employed, will be removed while the partially formed rod is shifted to expose the next series of spaces 14 to the particulate material filling station.

Thus, the aforesaid objects and advantages are 15 most effectively attained in that multiple filter rods are manufactured with a loose particulate filter section having optimum fill and density while maintaining relatively clean manufacturing conditions in confining the particulate material to the space 14 between filter components 12a and 12b. Although several somewhat preferred embodiments of the invention have been disclosed and described in detail herein, it should be understood that this invention is in no sense limited thereby and its scope is to be determined by that of the appended claims.

I claim:

1. A method of making cigarette mouthpiece rods divisible into individual mouthpieces which have a particulate component aligned coaxially with the other components, the method comprising the steps of:

a. feeding the other components in a coaxial alignment with a space therebetween;

b. completely enclosing the spaced other components in a continuous first wrapper having a width at least equal to the circumference of the other components and having preformed spaced openings therein positioned between the ends of the other components so that particulate material may pass through the openings to fill the spaces between the other components;

c. providing a source of the particulate material;

d. passing the enclosed spaced other components beneath the source of particulate material so as to align the openings in the continuous wrapper with the source;

e. introducing the particulate material into the space between the spaced other components through the openings defined by the continuous wrapper; and

f. completing the wrapping of the composite rod by sealing the openings, thereby forming a continuous composite rod.

2. The invention in accordance with claim 1 wherein the spaced other components are of different lengths.

3. The invention in accordance with claim 1 wherein the spaced other components are of double length and the completely wrapped continuous rod is subdivided by cutting it at intervals to thereby produce rods each of which contains at least one particulate section.

4. The invention in accordance with claim 3 wherein the continuous rod is subdivided by cutting each of the double length components approximately on center to thereby provide individual mouthpieces having a particulate section between sections of different character.

5. The invention in accordance with claim 1 wherein the components are secured to the initial wrapper prior to the introduction of the particulate material.

6. The invention in accordance with claim 1 wherein the initial wrapper is air permeable and suction is drawn therethrough as the particulate material is introduced into the spaces between components to thereby increase the rate at which the spaces are filled with particulate material.

7. The invention in accordance with claim 1 wherein the openings are sealed by applying a tape of sufficient width to cover said openings, securing the tape to the outer surfaces of said first wrapper.

8. The invention in accordance with claim 1 wherein a second wrapper is applied completely about the outer surfaces of the inner wrapper to seal said openings, said second wrapper having overlapped marginal side edges, securing said overlapped side edges to one another.

9. The invention in accordance with claim 1 wherein the first wrapper is notched at predetermined intervals along at least one of its marginal side edges to define said openings when said first wrap is applied about said

components.

10. The invention in accordance with claim 9 wherein the first wrapper is notched along both of the marginal side edges of the first wrapper to define said spaced openings.

11. The invention in accordance with claim 1 wherein the first wrapper is punctured at spaced intervals between its marginal side edges to define said openings.

12. The invention in accordance with claim 11 wherein the punctured openings are formed in said first wrapper after said first wrapper is applied to said components and before the particulate material is introduced into the space between the components.

13. The invention in accordance with claim 1 wherein the continuous first wrapper and the enclosed spaced components are fed to the source of particulate material intermittently and wherein the particulate material then is introduced through the openings into the space between components by metering jets, the first wrapper being thereafter moved away from said source.
